UNITED STATES PATENT OFFICE

WILLIAM D. CYPHERS, OF TULSA, OKLAHOMA, ASSIGNOR TO THE OHIO OIL CO., OF
FINDLAY, OHIO, A CORPORATION OF OHIO

DESIGN FOR A SERVICE STATION BUILDING

Application filed July 29, 1932. Serial No. 44,474. Term of patent 14 years.

To all whom it may concern:

Be it known that I, WILLIAM D. CYPHERS, a citizen of the United States, and a resident of Tulsa, in the county of Tulsa, and State of Oklahoma, have invented a new, original, and ornamental Design for a Service Station Building, of which the following is a specification.

Reference is had to the accompanying drawing forming part thereof.

In the drawing Figure 1 is a view in front elevation, illustrating my new design for a service station building, and Figure 2 is a plan view of Figure 1.

I claim:

The ornamental design for a service station building, as shown.

WILLIAM D. CYPHERS.
